UNITED STATES PATENT OFFICE.

EDWARD F. OTTO, OF KENOSHA, WISCONSIN.

SASH-FASTENER.

1,187,647.

Specification of Letters Patent. Patented June 20, 1916.

Application filed August 10, 1914. Serial No. 856,033.

To all whom it may concern:

Be it known that I, EDWARD F. OTTO, a citizen of the United States, residing at Kenosha, in the county of Kenosha and State of Wisconsin, have invented certain new and useful Improvements in Sash-Fasteners, of which the following is a specification, reference being had to the accompanying drawings.

10 This invention relates to new and useful improvements in sash fasteners and an object of this invention is the provision of a fastener which will lock the sashes when partly open or when entirely closed.

15 Another object of this invention is the provision of a fastener which when in operative position draws the sashes together, to prevent rattling of the same in windy or stormy weather.

20 With these and other objects in view, my invention consists in the novel construction, combination, and arrangement of parts to be hereinafter more fully described, claimed, and illustrated in the accompanying drawing, in which—

25 Figure 1 is a front elevational view of my improved fastener showing the same applied to use; Fig. 2 is a transverse sectional view thereof; Fig. 3 is a detail elevational view showing the locking bolt connected with the keeper plate; and Fig. 4 is a fragmentary elevational view of the keeper plate engaging end of the locking bolt.

30 Referring more particularly to the drawing, the numerals 1 and 2 designate the upper and lower sashes respectively of a window, and secured to one of the side rails of the upper sash is an elongated keeper plate 3 which extends vertically of the sash, the inner edge of the plate projecting inwardly of the inner edge of the side rail. Formed on the upper and lower ends of the keeper plate are inwardly projecting lugs 4, the lugs being vertically aligned, and being adapted for engagement with the inner edge of the side rail as shown in the drawing, to provide means for properly positioning the plate in an upright position, so that the plate may be quickly and accurately secured to the side rail by the screws 5 which extend through openings in the plate into engagement with the rail. The lower edge of the keeper plate is adapted to rest against the bottom rail of the upper sash, and formed in the projecting portion of the plate is a longitudinal series

of transversely elongated slots 6, the slots being of any desired number, and being spaced any suitable or desired distance apart. The upper and lower wall of each slot intermediate of its ends is provided with an angular recess 7, to enlarge the slots for a portion of their length, for a purpose which will be hereinafter more fully described.

35 Arranged upon the upper face of the top rail of the lower sash 2, is an open bottom casing 8, the casing being provided with oppositely extending longitudinally apertured flanges at its lower edge for engagement against the upper face of the rail, to receive suitable fastening devices by means of which the casing is secured to the top rail of the lower sash. The end walls of the casing are provided with suitable bolt 75 openings, and extending through the casing and projecting at its opposite ends through the bolt openings is a locking bolt 9, the bolt having a flattened shank 10 at its outer end on the extremity of which a head 11 is formed for engagement through the slot 6 in the keeper plate. A coiled expansion spring 12 is wound around the bolt within the casing, the outer end of the spring bearing against the outer wall of the casing, 85 and the inner end of the spring engaging a laterally extending pin 13 which projects from the bolt, the spring normally holding the bolt in its innermost position, and the pin 13 serving to limit the inward movement of the bolt by reason of its engagement against the inner wall of the casing. From the above it will be seen that the bolt is slidably and rotatably mounted in the casing, and the head 11 of the bolt is reduced adjacent the shank 10, to provide inwardly facing shoulders 14.

90 In the practical use of my improved fastener, with the plate 3 in its proper position on the upper sash, and the casing 8 carrying the bolt 9 in its position on the lower sash, the sashes may be locked in closed position by forcing the bolt 9 inwardly with the head 11 thereof arranged horizontally, so that the head may be passed through the 95 lowermost slot 6 in the keeper plate. When the head has been passed through the slot and the shank 10 of the bolt is engaged within the slot, the bolt is then rotated so as to dispose the head vertically, and as 100 the head is of greater length than the width of the slot, disengagement of the head from

the plate is prevented. Owing to the recesses 7 in the upper and lower walls of the slots, it will be seen that the reduced portion of the head 11 will engage within the angular recesses, so that the inwardly facing shoulders 14 formed by the reduced portion of the head engage the inner face of the plate above and below the enlarged portion of the slot, whereby accidental turning 10 of the bolt to aline the head with the slot is prevented. The tension of the spring 12 which forces the bolt inwardly, serves to draw the lower rail of the upper sash tightly against the upper rail of the lower 15 sash to prevent rattling of the sashes in stormy weather. When it is desired to move either of the sashes vertically, it is merely necessary to slide the bolt slightly to arrange the shank 10 of the bolt within the 20 slot, so that the bolt may be turned to aline the head thereof with the slot, in which position the tension of the spring will move the head out of the slot so that the sashes may be moved to the desired position, 25 whereupon the head of the bolt may be again disposed within the adjacent slot in the hereinbefore described manner. It will be seen that when the fastener is not desired for use, the spring 12 will maintain 30 the bolt in its normal position, so that the

sashes may be moved upwardly and downwardly without danger of the bolt engaging the keeper plate and preventing free movement of the sashes.

Having thus fully described my invention, 35 what I desire to claim and secure by Letters Patent is:—

A window fastening comprising a strip having an elongated slot formed therein, the slot being laterally extended at its sides, a 40 bolt casing, a bolt slidably and rotatably mounted in the casing and having a head on its outer end substantially the shape of said slot and being adapted for insertion through the slot, the bolt and head being rotatable 45 to dispose the head across the slot, the face of the head toward the bolt being formed on each side of the bolt with projecting shoulders adapted when the bolt is disposed across the slot to fit in said lateral extensions of the slot to thereby prevent a rotation of the bolt, and a spring urging the bolt away from the plate.

In testimony whereof I hereunto affix my signature in the presence of two witnesses. 55

EDWARD F. OTTO.
